(57) **CLAIM**

I claim the ornamental design for a buttstock, as shown and described.

DESCRIPTION

FIG. 1 a top/left side/front perspective view of the firearm handguard.

FIG. 2 a top/right side/front perspective view thereof.

FIG. 3 a bottom/left side/front perspective view thereof.

FIG. 4 a bottom/right side/front perspective view thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a right side elevation view thereof; and,

FIG. 10 is a left side elevation view thereof.

The broken lines are for illustrative purposes only and form no part of the claimed design.
